HAIR CUTTING MACHINE

Karl Marholt, Vienna, Austria

Application October 9, 1935, Serial No. 44,212
In Austria February 5, 1935

10 Claims. (Cl. 30—1)

My invention relates to hair cutting machines for removing hairs from cavities, for instance the nostrils or the ear opening, of the kind having two tubes with cutting teeth and slots on their end 5 rotatably arranged within each other. Machines of this type are operated by rotating the tubes relatively to each other. My invention relates particularly to the driving means for effecting such rotation by hand and aims to provide a 10 machine of the class described which may be easily and accurately operated by two fingers of the hand holding the same and enabling to effect the delicate operation of hair removing from cavities of the human body with great precision and 15 without any danger of severing the skin. For this purpose, it is of great importance to avoid any back-action of the cutting movement upon the hand holding the machine. According to my invention, therefore, a driving mechanism is provided 20 which makes it possible to effect the rotation of the tubes by pressing upon one or two lateral lever arms with the fingers of the hand holding the machine.

A feature of my invention consists in providing 25 a driving mechanism by virtue of which the cutting movement of the tubes does not involve any change in their direction, so that the operation may be performed with complete safety. In a preferred embodiment of the invention, the outer 30 tube remains in an unvarying position in relation to the holding hand while the cutting is effected by rotation of the inner tube in order to avoid any undesired movement and therefore also avoiding 35 any danger of bringing the cutting teeth in touch with the skin and cutting the same.

A further object of the invention is to provide a machine of this kind which may be easily dismounted and reassembled for cleaning purposes and which may also be cleaned in the assembled 40 state by leading a stream of air, water or any other cleaning agent through a bore passing through the inner tube.

The drawing shows the invention in an enlarged scale by way of example. Fig. 1 represents a side 45 elevation of the device, Fig. 2 a view from below and Fig. 3 a section through the tubes along the axis with the lever arms removed.

The outer of the two cylinders or tubes arranged within each other is designated by the reference 50 1, the inner by 2. The outer cylinder is provided at 3, the inner at 4 in a known manner with sharply edged teeth and slots, acting like shears if the cylinders are rotated relatively to each other. The inner cylinder is thickened at its 55 lower end and provided with two pins arranged

at opposite ends of a diameter, the ends of which are protected by bosses. On the outer cylinder 1 the two studs 7 are screwed in, on which the two lever arms 8 are rotatably mounted. These lever arms have U-shaped cross-section and embrace the two cylinders. A flange 9 on each of the two lever arms, lying in the plane of movement, is provided with a slot 10, in which one of the pins 6 engages, whereby a gear connection is provided which effects a rotation of the tubes 1 and 2 10 against each other, if the lever arms 8 are compressed. The flattened portions 5 of the thickened ends of the inner tube 2 enables a closer compression of the lever arms 8 in their end position. A spring 11 always holds the lever arms 15 apart, so that an easy operation with one hand is possible.

In order to allow an easy dismounting of the device for the purpose of cleaning it, the slots 10 are open towards the rear, so that the inner cylinder 2 may be easily pulled out. A screw 12, a pin under spring tension or the like serves to hold the tubes together. The screw 12 is screwed into the outer tube 1 and engages with its point a groove 13 arranged on a part or on the entire circumference of the inner tube 2.

The inner tube 2 is suitably provided in its longitudinal direction, with a bore passing therethrough and which may serve to conduct a cleaning agent (air, water, alcohol or the like), the arrangement of the gear elements being suitable so that they do not project into said bore.

When used, the parts 3 and 4 are introduced into the cavities, so that the hairs extend into the slots between the teeth. If the lever arms 8 are compressed, the tubes are rotated against each other and the hairs are clipped.

Several modifications are possible without leaving the scope of the invention. In particular, the spring 11 may be dispensed with, if the lever arms are provided with handles for the insertion of the holding fingers. The spring may also be fastened on both tubes 1 and 2 and may tend to rotate the same opposite to the direction of actuation. The gear elements 6 and 10 may also be 45 of other kind, for instance on the flanges 9, racks may be attached which are in mesh with a pinion gear on part 5.

The tubes may be cylindrical or may have another similar form, for instance the form of 50 truncated cones with the cutting teeth and slots on the smaller base.

What I claim is:

1. In a hair cutting machine, two tubes provided with cutting teeth and slots at their ends, 55

one tube being rotatably arranged within the other, driving means for rotating said tubes relatively to each other, said means comprising two systems of interlinked members, including a pair of levers adapted to be actuated by hand, one member of each system being fulcrumed on one tube and another member of each system being operatively connected to the other tube.

5. In a hair cutting machine, two tubes provided with cutting teeth and slots at their ends, one tube being rotatably arranged within the other, driving means for rotating said tubes relatively to each other, said means comprising two systems of interlinked members symmetrically arranged with respect to the tube axis, said members including a pair of levers adapted to be actuated by hand and symmetrically arranged with respect to the tube axis, one member of each system being fulcrumed on one tube and another 10 member of each system being operatively connected to the other tube.

15. In a hair cutting machine, two tubes provided with cutting teeth and slots at their ends, one tube being rotatably arranged within the other, driving means for rotating said tubes relatively to each other, said means comprising two systems of interlinked members including a pair of levers adapted to be actuated by hand, each of said levers swinging about an axis perpendicular to the tube axis, one member of each system being fulcrumed on one tube and another member of each system being operatively connected to the other tube.

20. In a hair cutting machine, two tubes provided with cutting teeth and slots at their ends, one tube being rotatably arranged within the other, driving means comprising two lateral lever arms mounted on one of said tubes to swing about an axis perpendicular to the tube axis, and means 25 attached on the other tube cooperating with said lever arms to rotate the tubes relatively to each other if the lever arms are pressed together by hand.

25. In a hair cutting machine, two tubes provided with cutting teeth and slots at their ends, one tube being rotatably arranged within the other, driving means comprising two lateral lever arms mounted on one of said tubes to swing about an axis perpendicular to the tube axis, spring 30 means forcing apart said lever arms and means attached on the other tube cooperating with said lever arms to rotate the tubes relatively to each other if the lever arms are pressed together by hand.

35. In a hair cutting machine, two tubes provided with cutting teeth and slots at their ends, one tube being rotatably arranged within each other, driving means comprising two lateral U-shaped lever arms embracing said tubes and 40 mounted on one of said tubes to swing about an axis perpendicular to the tube axis and means attached on the other tube cooperating with said lever arms to rotate the tubes relatively to each

other if the lever arms are pressed together by hand.

45. In a hair cutting machine, two tubes provided with cutting teeth and slots at their ends, one tube being rotatably arranged within each other, driving means comprising two lateral U-shaped lever arms embracing said tubes and 50 mounted on one of said tubes to swing about an axis perpendicular to the tube axis, each of said U-shaped lever arms having a flange extending in the direction of movement and provided with an aperture, radial pins arranged on the other tube engaging said apertures to rotate the tubes relatively to each other if the lever arms are 55 pressed together by hand.

5. In a hair cutting machine, two tubes provided with cutting teeth and slots at their ends, one tube being rotatably arranged within each other, driving means comprising two lateral U-shaped lever arms embracing said tubes and 10 mounted on the outer of said tubes to swing about an axis perpendicular to the tube axis, each of said U-shaped lever arms having a flange extending in the direction of movement and provided with a rearwardly open slot, radial pins 15 arranged on the inner, removable tube engaging said slots to rotate the tubes relatively to each other if the lever arms are pressed together by hand.

20. In a hair cutting machine, two tubes provided with cutting teeth and slots at their ends, one tube being rotatably arranged within each other, driving means comprising two lateral U-shaped lever arms embracing said tubes and 25 mounted on the outer of said tubes to swing about an axis perpendicular to the tube axis, each of said U-shaped lever arms having a flange extending in the direction of movement and provided with a rearwardly open slot, radial pins 30 arranged on the inner, removable tube engaging said slots 35 to rotate the tubes relatively to each other if the lever arms are pressed together by hand, the outer tube being provided with a fastening screw 40 engaging with its point a circumferential groove 45 on the inner tube.

45. In a hair cutting machine, two tubes having at their ends cutting teeth and slots, one tube being rotatably arranged within the other, the inner tube having a bore passing therethrough, driving means for rotating said tubes 50 relatively to each other, said means comprising two lateral U-shaped lever arms embracing said tubes and mounted on the outer of said tubes to swing about an axis perpendicular to the tube axis, each of said U-shaped lever arms having 55 a flange extending in the direction of its movement and provided with an aperture, radial pins arranged on the inner tube engaging said apertures to rotate the tubes relatively to each other if the lever arms are pressed together by hand, 60 said pins being so arranged as to not project into the bore of the inner tube.

KARL MARHOLT.
